METHOD OF MAKING PILE FABRICS

Charles Lyle, Buena Vista, Va., assignor to James Lees and Sons Company, Bridgeport, Pa., a corporation of Pennsylvania

Original application August 12, 1954, Serial No. 449,427.
Divided and this application March 8, 1955, Serial No. 492,884

6 Claims. (Cl. 139—7)

The present invention relates to a method of making pile fabrics and more particularly to producing carpet fabrics exhibiting the flexibility in design which is typical of Axminster-type fabrics. This application is a division of my co-pending application "Improved Pile Fabric and Method of Making the Same," Ser. No. 449,427, filed August 12, 1954, now abandoned.

Conventional Axminster-type fabrics are characterized by wide flexibility in the design of the pile surface. In such fabrics, it is possible to use an infinite number of color variations in the pile without substantially increasing the cost of the fabric. Figured Wilton-type fabrics, on the other hand, are costly by reason of the necessity to float the colored yarns not being used in the body of the base fabric underneath the upper weft shots. However, in conventional Axminster-type fabrics, the pile is not as dense as in the Wilton-type fabrics since two upper double weft shots are required for each weftwise row of pile loops. As a result, the conventional Axminster-type fabric exhibits a tendency to "grin" and expose the base fabric by reason of the separation of the individual legs of the pile tufts. The individual legs of pile tuft are separated by a double upper weft shot, since it is necessary to tie the pile tufts under a double weft shot.

In Wilton fabrics, on the other hand, it is possible to tie the pile tufts under only a single weft shot so that a dense pile may be obtained and the possibility of "grinning" is substantially reduced. However, as pointed out above, to obtain a variation in the pattern by using different colored pile yarns, it is necessary to carry the various colors of pile yarns in the base of the fabric, raising only the desired color of pile yarn out of the base fabric to form a tuft or loop.

With the foregoing in mind, a primary object of the present invention is to provide a method of producing a pile fabric wherein pile yarn tufts having varying characteristics are tied under individual strands of double upper weft shots, and wherein a substantial portion of each pile yarn in the fabric is disposed in the pile surface, only a very minor portion being retained in the base fabric, i. e., only a sufficient length of yarn to tie the pile tufts in place.

Another object of the present invention is to provide a method of weaving a pile fabric wherein substantial economy is effected by employing an Axminster-type loom to produce a carpet fabric having certain characteristics of the more expensively produced Wilton fabrics.

A further object of the invention is to produce a pile carpet fabric having a high ratio of pile yarn to backing yarn.

Still another object is to provide a method of weaving on an Axminster-type loom wherein substantial economy is effected by inserting a weftwise row of pile tufts for each double upper weft shot.

These and other objects of the invention and the various features and details of the construction and operation

2

thereof are more fully set forth hereinafter with reference to the accompanying drawing in which:

Fig. 1 is a warpwise sectional view of a fabric made in accordance with the present invention; and,

5 Figs. 2 to 6 are illustrations of a portion of an Axminster-type loom showing successive steps in the formation of a fabric made in accordance with the present invention, for example, as shown in Fig. 1.

The novel fabric of the present invention is shown in 10 Fig. 1. The fabric comprises a series of upper double weft shots 10a, 10b, 10c, etc., and lower double weft shots 11. The upper and lower double weft shots are bound together by chain warps 12, 12 respectively passing alternately above and below the upper and lower 15 double weft shots. A stuffer warp 13 is provided intermediate the upper and lower weft shots to separate the same and provide body to the ground fabric.

In accordance with the invention, pile tufts 15, 16, 17, 18, etc., are tied into the base fabric by passing the same 20 between the strands of the upper double weft shots and around an individual strand of said upper double weft shot. Thus, the yarn 15 originates at a given height above the base fabric, passes into the base fabric between the strands of the upper double weft shot 10a, around one 25 of the individual strands of said upper double weft shot 10a, and up to the level at which the opposite pile leg originated. Likewise, the pile yarn tuft 16 originates at the same level, passes between the strands of the upper double weft shot 10b, around one of the strands thereof, 30 and back up to the aforementioned level. It should be noted that the various pile tufts may have differing characteristics, for example as indicated by the shading thereon, and that it is not necessary to float the pile yarns in with the base fabric when they are not employed to form 35 pile tufts.

The novel method for forming the fabric described above is illustrated diagrammatically in Figs. 2 to 6 inclusive. As shown in the figures, the loom for weaving the fabric is somewhat similar to a conventional Axminster 40 loom. The loom comprises a breast plate 20 on which the substantially finished fabric F is carried to the breast-beam (not shown) for winding up. Spaced rearwardly from the breast plate 20 is a conventional reed 21 having mounted adjacent thereto a separator finger 22 arranged to operate as more fully set forth hereinafter. An auxiliary reed 23 is provided to operate from its normal position below the breast plate 20 in a generally circular path, rearwardly and upwardly towards the reed 21 and forwardly to the trailing edge of the breast plate 20, 45 then downwardly to its normal position shown in Fig. 2. A latch arm 33 is provided to operate adjacent the fell of the cloth to engage the weft shots. A conventional comb is provided at 24 which operates in the usual manner to wrap the pile tufts around the weft shots. If desired the comb may be replaced by a nose board mounted on the breast plate. The usual cutting knives are provided at 25, 25 to shear the pile tufts after they are formed in the base fabric. The loom is provided with 50 harness mechanism (not shown) to form a split shed and upper and lower needles 26 and 27 respectively operate to insert double weft shots into the upper and lower sheds respectively.

In the operation of the loom, the needles 26 and 27 insert upper and lower double weft shots into the upper 55 and lower sheds respectively formed by the harness mechanism. It is noted that the strands of the web shots are in vertical alignment when inserted by the needles, as shown in Fig. 2. A shuttle (not shown) operates to retain the double weft shots in the fabric upon withdrawal of the needle in conventional manner. Upon withdrawal of the needle, the separator finger 22 oper-

ates to engage and position an individual strand, in the present instance the upper strand of the upper double weft shot, back against the reed to separate the same from the other strand of the upper double weft shot. At this point in the operation, the auxiliary reed 23 is rocked rearwardly and upwardly behind the lower double weft shot and the remaining strand of the upper double weft shot. Thus, the elements are in the position shown in Fig. 3. It has been found possible to separate the upper weft shot solely by means of the auxiliary reed, in which event the separator finger 22 may be eliminated from the loom.

While the above-described operation is being performed, the tube frame 29 which carries the pile yarn P is actuated into the shed. During the actuation of the tube frame, the auxiliary reed 23 is rocked forwardly to the position shown in Fig. 4 in advance of the dipping of the tube frame 29 into the shed. At the same time, the latch arm 33 engages the strands carried by the auxiliary reed to hold the same in place, and if the separator finger 22 is employed, it releases the separated shot of the double upper weft shot, for example, by a latch member 31 pivoted to the separator finger as shown in Fig. 4. The separator finger 22 thereupon retracts, leaving the separated strand of the double upper weft shot in position in front of the reed 21.

The auxiliary reed continues its circular movement until it resumes its position below the breast plate 20, for example as shown in Fig. 5. The tube frame 29 continues its forward advance and is withdrawn to lay the pile yarn P against the strands of the weft shots which have been advanced to the fell of the fabric F by the auxiliary reed 23.

Simultaneously with the advance of the tube frame 29, the reed 21 carries the separated weft strand forwardly to a position against the pile yarn P and the latch arm 33 is retracted. The reed 21 engages the separated strand against the remaining strand of the double upper weft shot to grip the pile yarn P therebetween. The tube frame 29 thereupon retracts upwardly, simultaneously feeding out sufficient yarn to form the pile tuft, for example the tuft 15. At this point in the operation, the comb 24 is actuated to wrap the trailing end of the pile yarn P upwardly around the separated strand into the upright position indicated at 15 in Fig. 6. The knives 25, 25 are then operated to sever the tuft 15 from the yarn P and the tube frame 29 is retracted and is returned to its carrier chain (not shown). During this operation, the chain warps 12, 12 are shedded to reverse their position and hold the weft shots 10 and 11 in place in the fabric.

Thus, the elements are returned to their original position. The adjacent upper and lower double weft shots are inserted into the shed, and a tube frame carrying the pile yarn for the pile tuft 16 is picked off the carrier chain and brought into position for insertion of the pile tuft 16 into the fabric.

It should be noted that since the succeeding pile tufts are taken from pile yarns on succeeding tube frames, it is possible to obtain an infinite variation in the characteristics of the pile yarn inserted in the fabric. Since the pile tufts are tied under only a single strand of the weft shot, less of the pile yarn is retained in the base fabric; and the greater part of the yarn is employed to form the pile surface. It should be further noted that since the upper double weft shots and the lower double weft shots are each inserted by an individual needle, it is possible to form the lower double weft shots of a different material than that used for forming the upper double weft shots. This is advantageous since the lower weft shots must engage against the floor on which the carpet is placed and are subjected to greater abrasion than the upper weft shots. Thus, the upper weft shots may be relatively weak and the lower weft shots may be formed of material exhibiting a great abrasion resistance.

While a particular embodiment of the present invention has been herein illustrated and described, it is not intended to limit the invention to such disclosures, but changes and modifications may be made therein and thereto within the scope of the following claims. For example, the upper and lower shots need not be inserted simultaneously, whereby the same needle may insert both shots in sequence. An additional double weft shot may be inserted above or below the stuffer to form a fabric corresponding to the conventional three-shot Axminster fabric, or the lower weft shot and stuffer may be omitted to form a fabric corresponding to a one-shot Axminster fabric.

I claim:

1. The method of producing a pile carpet fabric comprising the steps of forming upper and lower sheds of base fabric warps, inserting a double upper weft shot and a double lower weft shot into the respective sheds and disposing the individual strands of said double upper weft shot in vertical alignment, holding the upper strand of said double upper weft shot, displacing said lower double weft shot forwardly to separate said upper double weft shot, inserting a pile yarn into said upper shed intermediate the strands of said separated upper double weft shot, releasing the upper strand of said double upper weft shot and bringing the strands of said separated upper double weft shot together, and wrapping the inserted pile yarn around the upper strand of said upper double weft shot.

2. The method of producing a pile carpet fabric comprising the steps of forming upper and lower sheds of base fabric warps, inserting a double upper weft shot and a double lower weft shot into the respective sheds and disposing the individual strands of said double upper weft shot in vertical alignment, displacing the upper strand of said double upper weft shot rearwardly, displacing said lower double weft shot and the lower strand of said upper double weft shot forwardly to separate said upper double weft shot, inserting a pile yarn into said upper shed intermediate the strands of said separated upper double weft shot, bringing the strands of said separated upper double weft shot together, and wrapping the inserted pile yarn around one of the strands of said upper double weft shot.

3. The method of producing a pile carpet fabric comprising the steps of forming upper and lower sheds of base fabric warps, simultaneously inserting a double upper weft shot and a double lower weft shot into the respective sheds and disposing the individual strands of said double upper weft shot in vertical alignment, displacing the upper strand of said double upper weft shot rearwardly and holding the same, displacing said lower double weft shot and the lower strand of said upper double weft shot forwardly to separate said upper double weft shot, inserting a pile yarn into said upper shed intermediate the strands of said separated upper double weft shot, releasing the upper strand of said double upper weft shot and bringing the strands of said separated upper double weft shot together, and wrapping the inserted pile yarn around the upper strand of said upper double weft shot.

4. The method of producing a pile carpet fabric comprising the steps of forming a shed of base fabric warps, inserting a double weft shot into said shed and disposing the individual strands of said double weft shot in vertical alignment, holding the upper strand of said double weft shot, displacing the lower strand of said double weft shot forwardly to separate the same, inserting a pile yarn into said shed intermediate the strands of said separated double weft shot, releasing the upper strand of said double weft shot and bringing the strands of said separated double weft shot together, and wrapping the inserted pile yarn around the upper strand of said double weft shot.

5. The method of producing a pile carpet fabric com-

prising the steps of forming a shed of base fabric warps, inserting a double weft shot into said shed and disposing the individual strands of said double weft shot in vertical alignment, displacing the upper strand of said double weft shot rearwardly, displacing the lower strand of said double weft shot forwardly to separate said double weft shot, inserting a pile yarn into said shed intermediate the strands of said separated double weft shot, bringing the strands of said separated double weft shot together, and wrapping the inserted pile yarn around one of the strands of said double weft shot.

6. The method of producing a pile carpet fabric comprising the steps of forming a shed of base fabric warps, inserting a double weft shot into said shed and disposing the individual strands of said double weft shot in vertical alignment, displacing the upper strand of said double

5
10
15

weft shot rearwardly and holding the same, displacing the lower strand of said double weft shot forwardly to separate said weft shot, inserting a pile yarn into said shed intermediate the strands of said separated weft shot, releasing the upper strand of said double weft shot and bringing the strands of said separated double weft shot together, and wrapping the inserted pile yarn around the upper strand of said double weft shot.
